FIGURE 1 is a perspective view of a tumbler or similar article, showing my new design,

The essential feature of my design resides in the provision on a tumbler of the configuration shown of an internal annular convex rib whose lower limit is substantially co-planar with the upper limit of the convex bottom wall of the tumbler.

I claim:

The ornamental design for a tumbler, as shown and described.
